(57) **CLAIM**

The ornamental design for a knife handle, as shown and described.

DESCRIPTION

FIG. 1 is a bottom left perspective view of a knife handle showing the new design;

FIG. 2 is a top left perspective view thereof;

FIG. 3 is a top right perspective view thereof;

FIG. 4 is a bottom right perspective view thereof;

FIG. 5 is a left side elevation view thereof;

FIG. 6 is a bottom plan view thereof;

FIG. 7 is a right-side elevation view thereof; and,

FIG. 8 is a top plan view thereof.

The broken lines depict portions of the knife handle in which the design is embodied that form no part of the claimed design.

1 Claim, 8 Drawing Sheets(56)
